ROOFING FASTENER

Lloyd K. Lockwood, Saginaw, Mich.

Application May 6, 1946, Serial No. 667,584

3 Claims. (Cl. 108—33)

1

This invention relates to fasteners for securing marginal overlap portions of panels or roofing units to each other and to a framework or sheathing. The present improvement pertains to clip-type fasteners having doubled-over portions provided with terminal penetrating points or projections.

An object of the invention is to provide such a fastener adapted to save time and thereby materially reduce the cost of packing, shipping, handling, and laying commercial roofing of many types including roll roofing, individual shingles, and strip shingles. For convenience such roofing elements will be referred to as "shingles."

Another object is to provide a fastener of the class described having a body portion so pre-formed that when placed on a shingle and struck with a roofer's hammer it shall fly up at one end, assuming a position in which it serves as an alignment gage for the next course of roofing, and from which it can be bent down nearly flatwise over the top face of an overlap shingle, either by hand or with a hammer. When thus bent down it can be set so as to clinch together the upper edge of an underlap shingle and the lower edge of an overlap shingle.

Another object is to provide a roofing fastener that can be readily applied to the shingles or roll units at the shingle mill so as to be ready for clinching when the shingle is put in place on the sheathing.

This is an application repeating a portion of an earlier application filed by me, and adding matter not disclosed in said earlier case and also matter disclosed, but not claimed therein.

My copending application, Serial No. 589,844, of which this is a continuation-in-part, describes and claims an improved fastener for securing marginal underlap and overlap portions of roofing units and the like to each other or to a framework or sheathing.

My copending application contains claims directed generally to the structure of roofing fasteners characterized by having an elongated body that lies substantially in a single plane, that is, approximately flat upon the face of a piece of roofing. It has fastening means for securing it to roofing pieces that are arranged in the usual manner, with underlap and overlap. Integral with the elongated body and intermediate its length, and projecting laterally or sidewise therefrom, is a member which upon being actuated by a hammer stroke, causes an end portion of the elongated body to rise up from its initial flatwise position on the face of the roofing, into up-

2

standing position where it becomes an accurately aligned stop-gage for the overlap portion of the roofing in the next course.

In my parent application the laterally projecting member is described and claimed as being capable of flexing so as to snap one end into upright position with a stroke of a roofing hammer. Thus the body is bent so as to extend over the top face of the overlap piece. It then can be flattened down by a final hammer blow.

My present invention, like that described in Serial No. 589,844, is provided with a laterally offset portion which, when struck with a roofer's hammer during the nailing operation on the roof, shifts the free end of gage portion of the fastener upwards, bringing it into position for aligning the next upper course of roofing. However, my earlier embodiment assumes that position by deformation of the metal of the fastener; whereas the embodiment set forth in the present application attains the same result, not by deforming the metal, but by giving the whole fastener a partial movement of rotation about its longitudinal axis. That is to say, the same results as with the earlier fastener are attained, but by a different and novel principle and mode of operation.

With the foregoing and certain other objects in view, which will appear later in the specifications, my invention comprises novel features of construction and combinations of parts described and claimed herein, which will be better understood in the course of the following detailed description, reference being had to the accompanying drawings which form a part of the specifications and by which preferred typical embodiments are illustrated.

It will be understood that various modifications may be resorted to within the scope of the appended claims without departing from the invention or sacrificing its advantages.

Fig. 1 is a perspective view of my improved fastener as it appears hooked on the upper edge of an underlap, but before being pronged thereto;

Fig. 2 is a cross-sectional detail on line 2—2 of Fig. 1, the section being taken in the direction indicated by arrows;

Fig. 3 is a side view showing the fastener in its final position after having been clinched to a single underlap and a single overlap, the roofing nail being omitted;

Fig. 4 is a detailed section on line 4—4 of Fig. 1;

Fig. 5 is a view of the fastener as seen from above when lying with its gaging member and shank in the plane of the drawing;

3

Fig. 6 is a part sectional end view of the parts shown in Fig. 5, the gaging member approximately flatwise on the roofing piece, a roofing nail being driven partly through the roofing and about to engage and rotate the fastener and bring the gaging member up into the dotted vertical position;

Fig. 7 is a plan view of the fastener, Fig. 5, showing the gaging member upright and the nail in cross-section;

Fig. 8 is a part sectional side view of the fastener showing the nail fully driven and the gaging member upright;

Fig. 9 is a small-scale cross-sectional view on line 9—9 of Fig. 8; and

Figs. 10 and 11 are plan views of modified forms of gage member, shank, and offset.

In a preferred form, illustrated in Figs. 1 to 9, my improved fastener comprises a shaft-like body portion which is substantially straight so it can lie flat on the face of a piece of roofing. It has on one part, 1, an end claw 2 which is recurved and also is laterally askew with respect to the part 1, as shown, Figs. 1, 2, 5, presenting a clincher, 3.

Numeral 4 designates another portion of the body having at its end a hook-like member 5 which is situated in the same plane, B, A, Fig. 6, with the axis of the body parts 1 and 4. Part 5 preferably has a prong 6.

A member 7 projects laterally from the body 1, 4, at a convenient point intermediate the claw 2 and the hook-like part 5.

Preferably, but not always necessarily, the outer extremity of projection 7 is formed with a lip 8 that extends downward, as shown, in two positions, disengaged from the roofing piece, in Fig. 6, and clinched thereto in Fig. 9. The laterally projecting member 7 is one of the operating features of my present improvement, by which hook 5 is shifted angularly, from the position Fig. 6 to the position Fig. 9, upon being engaged by the head of a roofing nail being driven through the roofing into the sheathing, as shown.

The nail head forces member 7 and its lip 8 to a firm anchorage on the roofing piece and in so doing partially rotates the body. That raises the hook-like part 5 up through a corresponding angle of rotation into substantially upright position, indicated by dotted lines in Fig. 6. The rotation of body 1 brings claw 2, Fig. 2, downward sidewise from the dotted position 3a to position 3. It is obvious that when the nail has been fully driven, as shown in Figs. 8 and 9, the nail fixes the fastener tight to the roof and also releases the end of clincher-claw 2 from its original clinched position, at 3a, on the roofing piece, Fig. 2.

It will be understood that for purposes of shipments of roofing with my fasteners attached, as is also the case with the fastener device disclosed in my earlier application, the end 3 of claw 2, which preferably is a prong, was first hooked into the bottom face of the piece of roofing, as shown at 3a, Fig. 2, and at 3, Fig. 6. Thus the fastener was secured to the roofing for shipment, and for convenience in laying the roofing. The hook-like part 5 lies substantially flatwise against the face of the roofing piece when the claw 2 and its pronged end 3 are clinched as

4

in Fig. 6. Then the fastener as a unit occupies a minimum of shipping space.

When parts 7 and 8 are forced by the nail into the position shown in Fig. 9, and parts 1 and 5 have rotated, then the hook-like member 5 stands upright, ready to gage and guide the roofing pieces of the next tier to be laid.

In Fig. 6 the prong 3 lies in the plane represented by the line A that includes the axis of the body 1, 4. The prong 8 on offset member 7 is in the plane C and the arm 5 and its prong 6 are in a plane represented by line B, and the upright position of arm 5 is shown by dotted lines, as already alluded to.

Thus it is seen that driving the nail rotates the body 1, 4 and shifts the hook-like member 5 into an upright operative position where it is adapted to serve as a gage and aligning element, by which an overlap portion of a subsequently laid tier of roofing will be accurately located on the underlap and can be clinched thereto as shown in Figs. 3 and 8.

In Fig. 10 a modified form of the offset parts 7 and 8 is shown at 7a, and in Fig. 11 the offset is shown in the form of a loop 7b through which the nail may be inserted. Any other appropriate form of offset, 7, may be employed provided it shall be adapted to rotate the parts 1 and 4 when encountered by the head of a roofing nail being driven.

Having thus described my invention, what I claim and desire to secure by Letters Patent is:

1. A fastener for roofing pieces comprising in combination a shaft-like partially rotatable body portion having at one end a claw recurved and askew and having at the other end a hook-like part situated in substantially the same plane that includes the axis of said body; said body having a laterally projecting member intermediate said claw and hook-like part and situated in a separate plane from either end of said body portion; said member adapted to shift angularly upon being engaged by the head of a roofing nail, and to shift said hook-like part into operative position for guiding, gaging, and alining an overlap portion of a subsequently laid tier of roofing.

2. A partially rotatable shaft-like body having at one end a recurved claw set askew; a hook-like member at the other end of the body; a projection extending laterally from said body intermediate the hook-like member and the claw; the hook-like member and lateral projection being arranged in a separate plane from either of said ends and constituting a positioning device adapted upon being actuated by a roofing nail in driving, to rotate the body and bring the hook-like member into substantially upright position; thus presenting a gage for alining an overlap of an upper tier of roofing with an underlap of a lower tier and for locating the outer portion of the hook-like member in position ready for use in clinching the said tiers together.

3. In a roofing fastener a rotatable body having a clincher at one end; a hook-like member at the other end; and a projection on said body, situated in a separate plane from either end of said fastener.
